UNITED STATES PATENT OFFICE

MAX M. FISCHER, OF BROOKLYN, NEW YORK

DESIGN FOR AN AUTOMOBILE RADIATOR SCREEN

Application filed August 15, 1930. Serial No. 36,677. Term of patent 7 years.

To all whom it may concern:

Be it known that I, MAX M. FISCHER, a citizen of the United States, and resident of Brooklyn, in the county of Kings and State of New York, have invented a new, original, and ornamental Design for an Automobile Radiator Screen, of which the following is a specification, reference being had to the accompanying drawing, forming a part thereof.

Fig. 1 represents a front elevation of an

automobile radiator screen, showing my new design, part of the mesh or grille work being broken away; and

Fig. 2 represents a side elevation of the same, viewed from the right of Fig. 1.

I claim:

The ornamental design for an automobile radiator screen, substantially as shown.

MAX M. FISCHER.
